UNITED STATES PATENT OFFICE.

JOSEPH EMANUEL SCHWIPPEL, OF ST. JOSEPH, MISSOURI.

IMPROVED MACHINE FOR MAKING GAS FROM VOLATILE OILS, &c.

Specification forming part of Letters Patent No. 87,299, dated February 23, 1869.

To all whom it may concern:

Be it known that I, JOSEPH EMANUEL SCHWIPPEL, of St. Joseph, in the county of Buchanan, and in the State of Missouri, have invented certain new and useful Improvements in Machines for Generating Gas; and I do hereby declare that the following is a full, clear, and exact description thereof, reference being had to the accompanying drawings, and to the letters of reference marked thereon.

The nature of my invention consists in the construction and general arrangement of a machine for generating gas from gasoline or paraffine-oil, which can be made of any size desired, so as to light private or public squares, or can be attached to lamp-posts, or in any place where lights are desired.

In order to enable others skilled in the art to which my invention appertains to make and use the same, I will now proceed to describe its construction and operation, referring to the annexed drawings, which form a part of this specification, and in which—

Figure 1 is a transverse vertical section, and Fig. 2 is a side view, of the machine, the front side being removed.

A represents a hollow cylinder, made of copper or other suitable material, through the center of which a shaft, B, passes. On this shaft, inside of the cylinder A, is placed a wheel, C, which is constructed on the principle of the long-known "cagnardelle," or French blowing-wheel, and is nothing more than a combination of a screw and a wheel, as seen in the drawings. A flue or pipe, D, allows the air to pass into the interior of the screw-wheel, which, by its rotation in the gasoline contained in the generator A, causes a steady current or draft of air to play in the interior of the machine and press toward the orifice of the burner or burners, which are or may be attached to the pipes connected with the generator.

So far, the screw-wheel C acts as a common bellows, blowing air into the generator A.

To combine its action as a blower with the qualification of an evaporator said screw-wheel is, on its outer surface, provided with a trimming, E, of common fringe of raw silk or other suitable material, said fringe being wound or attached closely around the wheel, so as to form a circular brush.

A sheet of copper or tin, F, (the protector,) is fastened in a half-circle to the inside of the cylinder A, so as to form the half of a cylinder within the former, but leaving a small space between them. This half-cylinder F is secured to the upper inner side of the generator, and is, on its lower side, also provided with fringe, G, against which the combined brush screw-wheel C is gently rubbing without impeding its motion. The protector F is further provided with small holes, a a, to let the gas pass, but to avoid any contact of the frame with the fluid.

From the top of the generator A, a pipe, H, leads to the burner. The opening b in the top of the generator, which is closed by a screw-stopper, c, and screw-cap d, is for the purpose of admitting the gasoline or paraffine-oil, from which the gas is generated, into the cylinder A. The fluid is admitted until it reaches the gage e on the rear side of the generator, when the opening b is securely closed.

When, now, the shaft B is turned the above-described brush screw-wheel C dips into the fluid, and with the fringe carries it up and moistens the fringe of the concave protector F, and, with the aid of the constant current of air passing and blowing through said fringe trimming, the gasoline evaporates into gas, and is forced in that form toward the burner.

The end of the shaft B passes through the end of the cylinder A, and a crank may be applied to the same, so as to turn the wheel C.

The machine as represented in the drawings, and which I denominate "Schwippe's Universal Luminator," is applicable to lamp-posts, as a few revolutions only of the machine are sufficient to generate gas enough for the time that street-lamps generally are lighted.

To light houses, public halls, &c., where a number of burners are used, the machine will of course be made on a larger scale, and then the wheel C may be turned by a weight, clock-work, or any other suitable means. The tube f at the bottom of the generator is for the purpose of emptying the remaining fluid when so desired. Around one end of the shaft B is placed a stuffing-box, g, by means of which more air can be admitted to the generator, if deemed necessary.

Having thus fully described my invention,

what I claim as new, and desire to secure by Letters Patent, is—

1. The arrangement of the generator A, having inlet b, outlet f, gage e, and pipe H, leading to the burner I, with the perforated protector F and its trimming G, all substantially as and for the purposes herein set forth.

2. In combination with the above, the shaft B, screw-wheel C, with its trimming E, and

air-pipe D, all substantially as and for the purposes herein set forth.

In testimony that I claim the foregoing I have hereunto set my hand this 2d day of January, 1869.

JOSEPH E. SCHWIPPEL.
